UNITED STATES PATENT OFFICE.

FREDERIC E. BENEDICT, OF OAKPARK, ILLINOIS.

WINDMILL-HEAD.

SPECIFICATION forming part of Letters Patent No. 711,148, dated October 14, 1902.

Application filed January 30, 1902. Serial No. 91,857. (No model.)

To all whom it may concern:

Be it known that I, FREDERIC E. BENEDICT, a citizen of the United States of America, residing at Oakpark, in the county of Cook and 5 State of Illinois, have invented certain new and useful Improvements in Windmill-Heads, of which the following is a specification.

My invention relates to improvements in back-geared pumping-windmills, its principal 10 object being to provide a construction which shall combine in the highest degree simplicity, cheapness of construction, durability, and the rigidly-fixed relation of those parts which should be immovable with reference to each 15 other.

The invention is fully described and explained in this specification and is shown in the accompanying drawings, in which—

Figure 1 is a side elevation of a windmill 20 embodying my improvements. Fig. 2 is a top plan thereof. Fig. 3 is a vertical section on the line 3 3, Fig. 1, the view being in the direction indicated by the arrow x in Fig. 1. Fig. 4 is a perspective view of the head or 25 turn-table of the mill. Fig. 5 is a vertical section on the line 5 5 of Fig. 2, the view being in the direction indicated by the arrow x' of Fig. 2. Fig. 6 is a horizontal section on the broken line 6 6 of Fig. 1, the view being down- 30 ward. Fig. 7 is a section on the line 7 7 of Fig. 1, the view being in the same direction as in Fig. 3; and Fig. 8 is a longitudinal section of the rocker-arm and the parts immediately connected therewith, the plane of section being on the line 8 8 of Fig. 3.

In the views, A, Fig. 1, designates a windmill-tower of any suitable construction supporting two shaft-bearings $a a$, arranged one above the other, the uppermost bearing being 40 in the top of the tower. On said upper bearing a rests the lower end of the tubular head or turn-table of the windmill, this head being provided with a downwardly-extending tube B' , preferably integral with it, and said tube 45 B' being journaled in the bearings $a a$, so as to hold the head in suitable relation to the tower and permit its free rotation. The head B is provided with two brackets $B^2 B^3$, cast integral with it and lying on opposite sides of 50 it, and it is likewise provided at its upper and lower ends with integrally-formed lugs $B^4 B^5$, which serve as supports for the vane

of the windmill, as is hereinafter explained. The bracket B^2 has at its outer end an integrally-formed horizontal shaft-bearing C, and 55 the bracket B^3 is formed with two integral shaft-bearings $C' C^2$, parallel to the bearing C, the bearing C' being near the middle of the bracket and the bearing C^2 being at the upper end thereof. The bearing C supports the 60 shaft D of the wind-wheel, which is journaled in it and extends from it at both ends, and on the left-hand end of the shaft, as shown in Fig. 1, are mounted the plates E E' of a wind-wheel of ordinary construction, while on the 65 right-hand end of the shaft is mounted a pinion F. The bearing C' supports a shaft D' , which is journaled in it, and on the right-hand end of this shaft, as shown in Fig. 1, is mounted a spur-gear F' , which engages the 70 pinion F and is driven thereby. The spur-gear F' is provided with a crank-pin f , which engages the lower end of a pitman G, and the upper end of this pitman is pivotally connected with the free end of a rocker-arm H, 75 the opposite end of the arm being pivotally supported by the upper end of the bracket B^3 . A pump-rod G' is pivotally supported at its upper end on the free end of the rocker-arm H and extends downward through the head B 80 and tube B' to the foot of the tower.

It will be seen that the bearings $C C'$ being cast integral with the head B and with each other are in rigidly-fixed relation, so that the proper engagement of the gearing is 85 a matter of certainty; that the rotation of the wind-wheel shaft gives a reduced rotation to the gear-wheel F' , which is the crank-plate of the windmill; that the pitman transmits reciprocal motion from the crank-plate to the 90 rocker-arm H and thence to the pump-rod G' , and that all the parts are so related as to secure strength, cheapness of construction, durability, and exactness of operation.

It is apparent that in any machine of this 95 class all rapidly-moving parts should be made as light as possible as a saving of power, while the weight of other substantially immovable parts is a mere matter of economy of construction. For this reason the rocker- 100 arm H of the construction shown in the drawings is preferably lighter and of smaller dimensions than the part of the bracket B^3 with which it is immediately connected. This

being the case, it is obvious that the greatest perfection and durability of alignment will be secured by making the pivot between the rocker-arm and the bracket integral with the 5 arm and journaling it in the bearing formed on the bracket. This construction is illustrated in Figs. 1 and 2, but more specifically in Fig. 8, which is a longitudinal section of the rocker-arm and of the parts immediately 10 connected therewith. In this figure the bearing C² at the upper end of the bracket B³ is shown in longitudinal section, and the corresponding end of the rocker-arm H is provided with a gudgeon h, (preferably a wrought 15 metal rod cast in the end of the rocker-arm,) this gudgeon being journaled in the bearing C². In the same way the opposite end of the rocker-arm H is formed with two gudgeons h' h², projecting in opposite directions from 20 it, the gudgeon h² being journaled in the upper end of the pitman G, while the gudgeon h' is journaled in an enlargement g at the upper end of the pump-rod G, and thus forms the support for the pump-rod.

25 The lugs B⁴ B⁵ of the head B form the support of the vane of the windmill, as is above suggested, the connection of the parts being thoroughly illustrated in Fig. 5, in which I is the main horizontal member of the vane, 30 and I' is a casting receiving the inner end of the member I and resting upon the lower lug B⁵. In the inner end of the casting I' is rigidly (and preferably integrally) secured an upwardly-extending tube I², the upper end 35 of which abuts against the upper lug B⁴ and prevents upward movement of the vane. Within this tube is a rod I³, extending through both lugs B⁴ B⁵ and connecting the vane therewith, and from the upper end of the rod I³ 40 an oblique brace I⁴ extends outward and downward to the end of the member I. On the tube I² is coiled a spring S, the upper end of which is hooked about the upper lug B⁴, while its lower end is formed with a projecting 45 arm s, which engages one end of a bolt s', the opposite end of said bolt being passed through an eye at the upper end of a vertical bolt s², which passes through the casting I' and through the inner end of the member I, and 50 thus holds them together. The end of the bolt s' which projects beyond the eye of the eyebolt s² is provided with a wing-nut N, by which it may be taken up or let out for the purpose of regulating the tension of the spring S. On 55 the casting I' is rigidly fastened a transverse horizontal bar K, one end of which is curved in a horizontal plane to form a stop K', abutting against the head B and forming a limit to the motion of the vane in one direction, 60 while the opposite end is turned upward, as clearly shown in Fig. 3, to form an arm K², for the purpose which will be presently explained. The attachments of the spring S are such that the tension of the spring tends 65 to swing the vane in the direction indicated by the arrow x' in Fig. 2, and thus to hold the stop K' against the head B, and the regu-

lation of the tension of the spring is for the purpose of adjusting the force with which the vane is thus held in its normal position. 70 When in this normal position, the vane is approximately in the vertical plane of the wind-wheel shaft and approximately at right angles to the plane of the wind-wheel; but it will be understood that the pressure of the 75 wind against the face of the wind-wheel tends to overcome the force of the spring S and to cause the wind-wheel to swing "out of the wind," or toward a position parallel to the 80 vane.

In the construction thus explained it is apparent that the tube I² not only prevents vertical displacement of the vane, but also forms a supporting-core for the spring S, and it is likewise obvious that the eyebolt s² has the 85 double function of connecting the vane member I and casting I' and of forming an abutment for the nut N, which serves to regulate the tension of the spring S.

In any mill of this general type means must 90 be provided for drawing the wind-wheel from its normal position by hand-power applied at the lower end of the tower, and Fig. 2 illustrates the means provided for this purpose in the construction set forth herein. In this 95 figure, L represents a cord fastened to the upper end of the arm K² of the bar K, and this cord passes about a horizontal pulley P (supported within a yoke c, formed integral with the bearing C, as shown in Fig. 4) and thence over a vertical pulley P', extending through a slot in the tubular head B, as shown in Fig. 6. It will be seen that the cord after passing over the vertical pulley P' is within the tubular head B, and it passes downward 105 to the foot of the tower and may be pulled 110 downward, with the effect of swinging the vane from its normal position, and thus drawing the stop K' away from the head B. The casting I' is formed with a horizontal projection I⁵, Figs. 2 and 6, the edge of which is adapted to strike the head B, and thus form a 115 stop limiting the movement of the vane as it is drawn out of the wind.

In a mill of this general type it is desirable 120 to provide means for automatically slackening the motion of the wind-wheel as it swings out of the wind as well as for practically locking the wind-wheel against rotation when the vane has been drawn from its normal position by means of the cord provided for that purpose. Figs. 1, 2, 6, and 7 illustrate a brake 125 mechanism provided for that purpose and forming part of the construction set forth in this application. In the mechanism thus 130 illustrated, E² is a conical brake-shoe sliding longitudinally on the bearing C, the bearing being provided with splines c', fitting in corresponding slots in the hub E³ of the brake-shoe, so as to prevent rotation of the shoe. 135 The brake-shoe is moved longitudinally with relation to the bearings C by means of a lever M, pivoted at one end to an arm c², formed on the yoke c on the bearing C. The lever

M is formed of two bars, (or of a single bar doubled upon itself at its center, as shown in Fig. 7,) each of the members being bent outward, so that the lever straddles the hub of the brake-shoe, and the free end of the lever is pivotally connected with the corresponding end of a connecting-rod N', which extends to and is pivotally connected with the casting I' of the vane. The connecting-rod N' is preferably made in two parts adjustably joined by means of a turnbuckle N², so as to secure the exact relation necessary to perfect operation of the device, and that end of the rod which is connected with the casting I' is curved, as shown in Fig. 6, so that the entire rod, which is of spring-steel, may transmit a yielding pressure to the brake-shoe. The lever M lies between suitable lugs on the hub E³ of the brake-shoe, and it is obvious that as the vane is swung from its normal position the movement transmitted through the connecting-rod N' and lever M must push the brake-shoe toward the plate E of the wind-wheel. A sufficient movement of the vane brings the brake-shoe into frictional contact with the plate, and thus arrests and prevents rotation of the wind-wheel.

Having now described and explained my invention, what I claim as new, and desire to secure by Letters Patent, is—

1. In a windmill of the class described, the combination with the tower, of the tubular turn-table B supported thereby and formed with the oppositely-placed brackets B²B³ supporting the parallel bearings C C' C², the wind-wheel shaft D journaled in the bearing C and provided with the pinion F, the second shaft D' journaled in the bearing C' and provided with the gear-wheel F' engaging the pinion F and having the crank-pin f, the rocker-arm H provided with the rigid gudgeon h journaled in the bearing C², the pitman G connecting the crank-pin f and the free end of the rocker-arm H, and the pump-rod G' carried by the upper end of the pitman, substantially as shown and described.

2. The combination with the tubular turn-table B having the brackets B²B³ and bearings C, C', C², of the shafts D D' and gears F F', the pitman G, the rocker-arm H formed at one end with a gudgeon journaled in the bearing C², and at the other end with two gudgeons, one journaled in the upper end of the pitman, and a pump-rod G', pivoted on the other of said gudgeons and supported thereby.

3. In a windmill of the class described, the combination with the tubular turn-table B formed with lugs B⁴ B⁵ at its upper and lower ends, of a vane-casting I' resting on said lower

lug, a vane member I entering said casting and secured therein by means of the eyebolt s², a tube I² set in the vane-casting and abutting against the upper lug B⁴, a connecting-rod I³ passing through said lugs and extending longitudinally of said tube, a spring coiled about said tube and connected with the upper lug, an arm projecting from the lower end of said spring, a bolt engaging said arm and passing through the eye of said eyebolt, and a nut mounted on said bolt and abutting against said eye and serving to regulate the tension of said spring.

4. The combination with the tubular turn-table B having the lugs B⁴ B⁵, of the casting I' resting on the lower lug, the vane member I entering said casting and connected therewith by means of the eyebolt s², a suitable pivot connecting said vane-casting with said lug B⁵, a coil-spring S engaging said upper lug B⁴ and having a projecting arm s at its lower end, a bolt s' engaging said spring-arm and passing through the eye of said eyebolt, and a nut N engaging the end of said bolt s' and serving to regulate the tension of the spring.

5. The combination with the tubular head, of the vane-casting pivoted thereto and supporting the vane, the wind-wheel shaft journaled in a bearing on the head and provided with a plate E, the sliding, non-rotating brake-shoe E² adapted to impinge upon the plate E, the operating-lever M engaging said brake-shoe and adapted to move it longitudinally in either direction, and the spring-steel connecting-rod N' interposed between said lever and said vane-casting, whereby the movement of the vane in one direction may press the brake-shoe against the plate, with a yielding force.

6. The combination with the head B, of the vane-casting I' pivoted thereto and supporting the vane, the wind-wheel shaft D journaled in a bearing on the head, the plate E mounted on the wind-wheel shaft, the sliding, non-rotating brake-shoe E² adapted to impinge upon the plate, the operating-lever for sliding said brake-shoe, and the connecting-rod N' interposed between said lever and said vane-casting, said rod being made up of two parts connected by a turnbuckle N², whereby its length may be regulated.

In witness whereof I have hereunto set my hand, at Chicago, in the county of Cook and State of Illinois, this 27th day of January, 1102.

FREDERIC E. BENEDICT.
